UNITED STATES PATENT OFFICE

109,745

DESIGN FOR A TABLE

Edward V. Trudo, Weston, Mass., assignor to
Trudo Manufacturing Company, Weston, Mass.,
a corporation of Massachusetts

Application November 6, 1937, Serial No. 72,663

Term of patent 14 years

To all whom it may concern:

Be it known that I, Edward V. Trudo, a citizen of the United States, residing at Weston, county of Middlesex, and Commonwealth of Massachusetts, have invented a new, original, and ornamental Design for a Table, of which the following is a specification, reference being had to the accompanying drawing, forming a part thereof.

In the drawing:

Fig. 1 is a perspective view of the table showing my design; and

Fig. 2 is a cross-sectional view thereof, taken on the line 2—2 of Fig. 1.

I claim:

The ornamental design for a table, substantially as shown.

EDWARD V. TRUDO.
